UNITED STATES PATENT OFFICE

WERNER SCHMID, OF WHITE PLAINS, NEW YORK, ASSIGNOR TO DUPLEX SILK CORPORATION, OF NEW YORK, N. Y., A CORPORATION OF DELAWARE

DESIGN FOR A TEXTILE FABRIC

Application filed September 30, 1931. Serial No. 41,268. Term of patent 3½ years.

To all whom it may concern:

Be it known that I, WERNER SCHMID, a citizen of the United States, residing in White Plains, county of Westchester, State of New York, have invented a certain new, original, and ornamental Design for a Textile Fabric, of which the following is a specification, reference being had to the accompanying drawing, forming part thereof.

The figure is a plan view of a textile fabric showing my new design.

The dot and dash lines on the drawing outline the design unit, which unit is repeated in regular succession, as indicated by the extensions beyond the unit boundaries.

I claim:

The ornamental design for a textile fabric substantially as shown and described.

WERNER SCHMID.
